US0D1011121S

(12) **United States Design Patent** (10) **Patent No.:** **US D1,011,121 S**
(45) **Date of Patent:** **** Jan. 16, 2024**

(54) **COOKING STOVE FOR CAMPING**

(71) Applicant: **Lihui Lin**, Jinhua (CN)

(72) Inventor: **Lihui Lin**, Jinhua (CN)

(**) Term: **15 Years**

(21) Appl. No.: **35/514,721**

(22) Filed: **Jun. 28, 2022**

(80) **Hague Agreement Data**

Int. Filing Date: **Jun. 28, 2022**

Int. Reg. No.: **DM/222004**

Int. Reg. Date: **Jun. 28, 2022**

Int. Reg. Pub. Date: **Jul. 15, 2022**

(30) **Foreign Application Priority Data**

Apr. 29, 2022 (CN) 202230254814.3

(51) **LOC (14) Cl.** **07-02**

(52) **U.S. Cl.**

USPC **D7/332; D7/334**

(57) **CLAIM**

The ornamental design for a cooking stove for camping, as shown and described.

DESCRIPTION

1. Cooking stove for camping

1.1: Perspective

1.2: Perspective

1.3: Front

1.4: Back

1.5: Top

1.6: Bottom

1.7: Left

1.8: Right

The portions of the cooking stove for camping shown in broken lines form no part of the claimed design.

1 Claim, 8 Drawing Sheets
